UNITED STATES PATENT OFFICE.

JESSEY F. HARRELL, OF MONROE TOWNSHIP, MADISON COUNTY, INDIANA.

OIL-GAS GENERATOR AND BURNER FOR STOVES.

964,775.

Specification of Letters Patent. Patented July 19, 1910.

Application filed May 6, 1908, Serial No. 431,074. Renewed May 21, 1910. Serial No. 562,769.

To all whom it may concern:

Be it known that I, JESSEY F. HARRELL, a citizen of the United States, residing in Monroe township, in the county of Madison and State of Indiana, have invented certain new and useful Improvements in Oil-Gas Generators and Burners for Stoves; and I do declare the following to be a full, clear, and exact description of the invention, reference being had to the accompanying drawings, and to the letters and figures of reference marked thereon, which form a part of this specification.

This invention relates to apparatus whereby hydro-carbon oil may be converted into gaseous fluid and consumed as fuel for producing heat in furnaces or fire-boxes of stoves, being adapted especially for use in cooking stoves or ranges.

20 The object of the invention is to provide a reliable, efficient and economical oil gas generator and burner for domestic use and which may be adapted for various other uses, a particular object being to provide 25 apparatus of the above mentioned character that may be readily applied to cooking stoves without requiring material alteration of the stoves, so as to be applicable to stoves already in use for using other fuels.

30 With the above mentioned and minor objects in view, the invention consists in an improved oil gas generator and burner comprising certain novel features of construction, and parts and combinations and arrangements of parts, as hereinafter particularly described and defined in the accompanying claims.

Referring to the drawings, Figure 1 is a fragmentary vertical central sectional view 40 longitudinally of the fire-box of a cooking stove and showing the approved apparatus in elevation in connection therewith; Fig. 2, a top plan of the improved apparatus; Fig. 3, a vertical sectional view of the apparatus 45 on the plane of the line A—A in Fig. 2; Fig. 4, a sectional view of the gas regulating valve as on the plane of the line B in Fig. 3; Fig. 5, a top plan of the regulating valve, and Fig. 6, a perspective view of the 50 supporting stand of the apparatus and the pan on which heat is generated for starting the operation of the apparatus, the pan being minus the absorbent top thereof.

Similar reference characters in the different figures of the drawings indicate corre-

sponding elements or features of construction.

The stove with which the apparatus is preferably adapted to be used comprises a main part 1, portions of which form parts 60 of the fire-box in which are grate-bars 2, the stove having a top 3, a fire-box back 4 and a side door 5.

The supporting stand of the apparatus comprises a base-plate 6, on the ends of which are upright supports 7 and 7' provided on the inner sides thereof with ledges 8 and 8' arranged somewhat above the plate 6 and below the tops of the upright supports, the latter being braced by a pair of 70 ribs 9 and 9'. The pan 10, having a marginal upright rim 11, is placed on the ledges 8 and 8' removably, and it has an aperture 12 near the middle thereof that is surrounded by an upright rim 13, the pan having a 75 recess 14 in one side near one end thereof and also a recess 15 in the opposite side thereof midway between the ends of the pan. The base-plate 6 is oblong in plan so as to approximately cover the grate-bars, and the 80 pan 10 is preferably of the same dimensions in plan as the base-plate 6. A clamp 16 is connected to the base-plate 6 near the upright support 7', and another clamp 17 is connected also to the base-plate near the 85 middle portion thereof. The upright support 7' has an aperture 18 therein below the pan 10, and another aperture 19 above the plane of the pan, the support 7 having an aperture 19' therein above the plane of the 90 pan, the apertures 19 and 19' being in alignment and arranged near the forward edges of the supports. The support 7' has a saddle-bearing 20, and the support 7 has a similar bearing 20' in the top thereof for supporting the main burner which comprises a tube 21 that is placed removably on the bearings in horizontal position, and it has apertures 22 in the uppermost portions of the wall thereof, the ends of the tube being 100 closed by caps 23 and 23'. The under side of the middle portion of the burner 21 is provided with an inlet tube 24 which serves as a part of a mixer so that atmospheric air 105 may be mixed with gas entering the tube to the main burner.

A supply pipe for conveying oil, and a part of which forms a generating coil in which the oil is converted into gas and conveyed to the burner, comprises a horizontal 110

portion 25 that is secured on the base-plate 6 by the clamp 16 and extends in one direction through a suitable opening at the bottom of the door 5 and has a valve 26 connected thereto for admitting and regulating the flow of oil to the pipe. The pipe comprises also an upright portion 27 that extends in the recess 14 of the pan 10 and upward past the front of the main burner, and 10 a horizontal portion 28 continuing from the upright portion slightly above the horizontal plane of the top of the burner and forward of the vertical plane of the front of the burner, nearly to the end of the burner 15 that is farthest from the door 5, the pipe having a curved portion 29 that extends from the portion 28 under the cap 23 of the burner and upward at the rear side of the burner, and a horizontal portion 30 extending 20 from the curved portion parallel with the horizontal portion 28 toward the door 5 and has a vertical portion 31 extending downward therefrom in the recess 15 of the pan, and has a horizontal portion 32 connected therewith that is secured by a clamp 17 to the base-plate 6, the portion 32 having an upright portion 33 connected therewith which is connected to the body 34 of a feed valve by means of a flange 34' with which 30 the valve body is provided, the valve body having a valve-seat 35 therein from which extends a discharge port 36 that is formed in a projection 36' on one side of the valve body, the orifice of the port being adapted 35 to deliver a jet upward into the inlet-tube 24, the valve body being arranged slightly below the lower end of the inlet-tube so that when a jet of gas escapes from the port it will mix with air that will be drawn into 40 the inlet-tube or mixing-tube, as is customary in burning gas. A needle feed valve 37 is adapted to operate on the valve-seat 35 to either close or open the port 36 and has a stem 38 mounted in the valve body 34 and provided with screw-threads 39 that are screwed into the valve body and having a 45 packing-nut 40, and an operating-handle 41 that is on the end of the stem, the stem extending through a suitable opening in the door 5 and also through the aperture 18 in the support 7'. A supply-pipe 42 is connected to the valve 26, and has an oil reservoir 43 connected therewith. The reservoir may be arranged at sufficient height to create 50 gravity pressure, or pressure for feeding oil to the burner may be obtained as is customary by suitably creating air pressure in the reservoir if the latter be placed at a relatively low level.

55 60 A trough 44 is provided that is supported in the apertures 19 and 19' and has small perforations 45 in the sides thereof, the ends of the trough having caps 46 and 46' thereon, so that the trough extends above the pan 10 and nearly under the main burner. A

priming pipe 47 is connected to the cap 46' and extends alongside of the portion 25 of the main supply-pipe through the door 5, and has a valve 48 connected thereto which is connected by a pipe 49 with the main supply-pipe 42 for admitting oil to the trough.

The pan 10 has a top 50 that is composed of suitable absorbent material such as asbestos-board to receive and absorb oil from the trough 44 when starting the burner to operate.

In practical use a small quantity of oil is admitted through the valve 48 into the trough 44 by which the oil is distributed onto the absorbent-top 50, on the top of which gaseous fluid will form that may be ignited, and the resulting flame will heat the main burner and also the generator formed of the pipe portions 28 and 30, and the valve 26 should then be opened (if not previously opened) to admit oil to the generator to be heated and thus converted into gas, and when gas has been formed the handle 41 may be turned slightly to admit 90 gas and air mixed therewith into the burner at which ignition will take place from the flame in the pan beneath, and any oil remaining in the trough will be consumed and add its heat to the burner. After having 95 used as much oil as may be necessary for starting the burner, the valve 48 should be closed and then the proper supply of oil will be regulated by the valve 26 and the quantity of gas regulated by the manipulation 100 of the valve-stem 38. When it becomes necessary or desirable to clean or repair the apparatus, the stove lids may be removed, and then the main burner may be lifted 105 freely from its support, after which the pan 10 may be slightly tilted on its support so that the base-plate 6 will then be accessible, and the packing-nut 40 may be readjusted or 110 packing applied without requiring disconnection of the pipes or other portions of the apparatus.

Having thus described the invention what is claimed as new, is—

1. In an oil gas generator and burner, the combination of a supporting stand comprising a base plate having an upright supporting plate on each end thereof, each plate having a ledge on the inner side thereof and having also a saddle-bearing on the top thereof, a pan supported on the ledges and having an absorbent noncombustible top, and a trough supported above the top of the pan, with a burner supported on the saddle-bearings, and a generator pipe leading to the burner. 115 120 125

2. In an oil gas generator and burner, the combination of a supporting frame, a burner mounted on the frame and having an inlet tube, a generator pipe having a portion thereof attached to the frame and 130

two upright portions at opposite sides of the burner, the pipe having also a curved portion extending under an end of the burner and two horizontal portions extending from 5 the curved portion to the upright portions, one of the upright portions having a short horizontal portion at the lower end thereof that is attached to the frame, said short portion having a short upright portion connected thereto, and a valve connected with said short upright portion under the inlet tube of the burner.

3. In an oil gas generator and burner, the combination of a supporting frame, a pan 15 mounted on the frame and having an aperture therein and having also an upright rim extending about the aperture, a burner mounted on the frame above the pan and having an inlet tube attached to the under 20 side thereof and extending through the aperture, a generator pipe attached to the frame and terminating below the pan opposite the inlet tube, a valve body attached to the terminal end of the pipe and having a 25 projection on the side thereof, the body having a duct therein extending through said projection, and a valve in said body to close or open said duct.

4. In an oil gas generator and burner, the combination of a supporting stand comprising 30 a base plate and two upright support-

ing plates, each upright supporting plate having a ledge thereon and an aperture therein above the plane of the ledges, a pan mounted on the ledges and having an aperture therein and having also a recess in each side thereof, a rim on the top of the pan at the edge thereof, a rim on the pan extending about the aperture, an absorbent non-combustible top on the pan, a trough mounted 35 in the apertures of the upright supporting plates above the pan, a burner mounted on the stand above the pan, an inlet tube attached to the burner and extending through the aperture of the pan, a combined supply 40 and generator pipe extending in the recesses of the pan and under an end of the burner and also along the burner and terminating under the pan opposite the inlet tube, a regulating valve connected to the terminal 45 end of the pipe, an inlet valve connected to the inlet end of the pipe, a main supply pipe connected to the inlet valve, a priming pipe connected to the trough, and an inlet valve connected to the priming pipe and 50 connected with the main supply pipe.

In testimony whereof, I affix my signature in presence of two witnesses.

JESSEY F. HARRELL.
